DISTRIBUTOR POINT GRINDER

Filed Jan. 14, 1935

Fig. 1

UNITED STATES PATENT OFFICE

2,051,309

DISTRIBUTOR POINT GRINDER

Harry J. McConnell and Robert G. McConnell,
Springfield, Ill.

Application January 14, 1935, Serial No. 1,622

6 Claims. (Cl. 51—241)

This invention relates to grinding mechanism, and, more particularly, to manually operated mechanism for grinding distributor breaker points and the like.

One of the objects of the invention is the provision of a new and improved device for simultaneously grinding the two breaker points of a distributor and having novel means for adjusting the grinder element.

Another object of the invention is the provision of a new and improved means for slidably and rotatably holding the grinder supporting arm and securing the same in adjusted position.

A still further object of the invention is the provision of a new and improved breaker point grinding device which is inexpensive to manufacture, composed of few parts, easily assembled, efficient in operation and having a universal adjustment, light and simple in construction, and which may be readily attached in position on a distributor box or bowl.

Other and further objects and advantages of the invention will appear from the following description, taken in connection with the accompanying drawing, in which:

Fig. 1 is a perspective view of a distributor of an automobile, with parts removed and parts broken away, and showing the invention in position for grinding the spark points;

Fig. 2 is a vertical section of the device through the supporting arm and clamping link member; and

Fig. 3 is a section on the line 3—3 of Fig. 2.

Referring now to the drawing, the reference character 10 designates a conventional distributor with the cap or cover removed for the sake of clearness. As is usual in such constructions, the distributor comprises the housing 11 within which the distributor shaft 12 extends. This shaft is flattened at its upper end at one or both sides as at 13 for engaging the rotor or distributor brush in the usual manner. A cam 14 is mounted on the shaft for operating the movable spring-pressed contact arm 15 which is pivoted at 16. This arm is provided at its free end with a contact point 17 which in turn is adapted to make intermittent contact with a fixed contact point 18 on the contact support 19. The housing is also provided with clips 20 which are adapted to engage the cap for holding the same in position on the housing. Since the details of the distributor are of the usual or any well-known construction and constitute no part of the present invention, it is not thought necessary to further illustrate or describe the same.

In electrical devices having breaker points, as, for instance, the make and break contacts of a distributor for the ignition system of internal combustion engines and the like, it is desirable that these points be maintained smooth in order that the maximum spark may be delivered by the spark plugs which are supplied with electrical energy through these points.

Extended use of the distributor results in wearing away of the breaker points and often the contacting surface of these points become irregular by the formation of projections and depressions on the contacting faces thereof which materially affect the operation of the ignition system by improper discharge of the spark. The present invention is designed for the purpose of grinding the contacting faces of these points to make them smooth whereby the discharge controlled by them will be concentrated and the ignition system operate to greater advantage.

Referring especially to Figs. 1 and 2, the grinding device comprises a support 21 which is preferably, though not necessarily, in the form of a clamp having the clamping jaws 22 and 23 with the thumbscrew 24 extending through one of the jaws for attaching the support to the side wall of the distributor housing, as clearly shown in Fig. 1 of the drawing.

The support 21 has an upwardly extending projection 25 on which a ball member 26 is rigidly mounted, as by being threaded thereon. A link member 27 has one end provided with a split clamp 28 having a socket 29 for engaging the ball 26 for forming an adjustable universal joint.

The opposite end of the link member 27 is also in the form of a split clamp 31 having a socket 32 for engaging a clamping ball member 33 for forming an adjustable universal joint, as will presently appear. The ends of the split clamp members 28 and 31 are turned in opposite directions and a thumb screw 34 extends through the free end of the clamp 28 and through the body of the link member and is threaded into the free end of the clamp 31, whereby universal adjustment may be had and on tightening the thumb screw 34, the link member is rigidly secured in adjusted position relative to both of the clamping ball members 26 and 33.

Slidably and rotatably mounted in the clamping ball 33 is a supporting arm 35. The clamping ball member 33 is provided with slots 36 that divide the member into clamping portions which are adapted to be clamped against the supporting arm for holding the same in adjusted position. The supporting arm 35 is hollow and is prefer-

ably curved at its lower end, whereby the same may be more readily adjusted to a position for grinding the breaker points of a distributor, as will presently appear. A flexible shaft 37 extends 5 through the arm 35 and has mounted on its upper end a crank 38 in any suitable manner, and on its lower end a grinder or grinding disk 39 is adapted to be attached by any appropriate means. The flexible shaft 37 may be of any 10 suitable construction. In the form shown, which is by way of example only, a rod 41 constitutes the end to which the crank 38 is attached. The outer end of the rod 41 is threaded for receiving a threaded washer 42 which limits the inward 15 movement of said rod. As shown, more particularly in Fig. 2, the crank 38 is provided with a threaded aperture for engaging the threaded end of the rod. The opposite, or lower end of the flexible shaft comprises a closely wound elongated 20 coil of wire or the like, the upper end of which is rigidly connected to the inner end of the rod 41 in any suitable manner, as by providing a recess on the end of the rod into which the flexible portion of the shaft extends, and is held therein 25 by any suitable means as by distorting the side walls of the aperture, or by means of solder.

The lower end of the flexible shaft has attached thereto a head 44 having a collar or shoulder 45 rigidly mounted thereon, which is adapted to engage the lower end of the supporting arm 35 for limiting the upward movement of the flexible shaft and to constitute an abutment against which the grinder element or grinding disk 39 is adapted to be clamped, the head 44 being provided with a threaded pin 46 extending axially therefrom for receiving the grinding element. The grinding element is held on the pin by a thumb nut 47.

It will thus be seen that by loosening the single 40 thumb screw 24 the grinder may be adjusted to any desired position about the clamp 21 and be rigidly secured in adjusted position by tightening the thumb screw.

When the parts are assembled, the rotation of 45 the crank 38 will cause corresponding rotation of the grinder element 39 through the flexible shaft 37. In the use of the device, the support 21 is preferably clamped on the side wall of the housing, as shown in Fig. 1, the thumb screw 34 50 loosened and the clamping link and supporting arm so adjusted that the grinder element 39 will be between the spark points 16 and 17, the cam 14 having previously been turned to a position in which the two breaker points are normally in 55 contact. The arm 15 having been moved outwardly, and the disk placed between two points, the arm 15 is released. The plane of the grinder element 39 is so adjusted that it will be at right angles to the axis of the two points, 60 and after the parts are properly adjusted, the thumb screw 34 is tightened to hold the parts in adjusted position. The crank 38 may then be turned for grinding both points simultaneously.

The spring pressed arm 15 will afford sufficient 65 pressure during the grinding operation. A few turns of the crank are usually sufficient. The grinder element may be of any suitable construction, such, for instance, as the conventional composition grinder disks obtainable in the market.

While the device is especially well adapted for the grinding of the breaker points of distributors, it is understood that it may be used in other relations, as occasion may require.

It is thought from the foregoing taken in connection with the accompanying drawing that the construction and operation of our device will be apparent to those skilled in the art, and that changes in size, shape, proportion and details of construction may be made without departing from the spirit and scope of the appended claims.

We claim as our invention:—

1. In a distributor point grinder, an attaching clamp member, an adjusting element connected to said member by a universal joint, a supporting arm adjustably connected to said element, a flexible drive shaft extending through said arm, a grinder element attached to said shaft at one end of said arm, said arm having a sharp bend adjacent to said element, and a crank arm on said shaft at the other end of said arm.

2. A distributor point grinder comprising a support, a grinder supporting arm having a laterally extending lower end, a grinder element, means including a drive shaft extending through said arm for rotating said grinder element, a sliding and universal connection between said arm and support, means for clamping said arm in adjusted position on said support, and a downwardly opening clamp on said support for detachably connecting said support to the upstanding wall of a distributor housing.

3. In combination, a grinder element, a supporting arm for said element, said arm having a sharp bend adjacent said grinder element, means for rotating said element including a flexible shaft, a support, means for rotatably, pivotally and slidably connecting said arm to said support, clamping means for rigidly connecting the support to an upstanding wall of a distributor housing, and means for adjustably rigidly connecting said arm to said support.

4. In a grinder for breaker points, a hollow supporting arm having a bent end, a drive shaft extending through said arm, a grinder element 45 on the end of said shaft adjacent the bent end of said arm, a crank on the opposite end of said arm, a support, means connecting said arm to said support for universal movement of said arm and means for clamping said support to the side 50 wall of a distributor housing whereby said breaker points may be ground.

5. In a grinder for distributor points, a support, a supporting arm having a curved portion, a grinder carried by said curved portion, means carried by said arm for operating said grinder, means for slidably and pivotally supporting said arm from said support and clamping means for connecting said support to the wall of a distributor housing.

6. In a device of the class described, a clamping member comprising a body portion having a loop at each end, a socket in each loop, the free ends of said body portion being on opposite sides thereof, and a single element engaging said ends and extending through said body portion for simultaneously contracting said sockets.

HARRY J. McCONNELL.
ROBT. G. McCONNELL.
